J. W. CLEGG,
COMBING MACHINE.
APPLICATION FILED FEB. 12, 1920.

1,402,569.

Patented Jan. 3, 1922.

INVENTOR:
James William Clegg
By Mr. Wallace White
ATTY.

UNITED STATES PATENT OFFICE.

JAMES WILLIAM CLEGG, OF OLDHAM, ENGLAND.

COMBING MACHINE.

1,402,569.

Specification of Letters Patent.

Patented Jan. 3, 1922.

Application filed February 12, 1920. Serial No. 358,290.

(GRANTED UNDER THE PROVISIONS OF THE ACT OF MARCH 3, 1921, 41 STAT. L., 1313.)

To all whom it may concern:

Be it known that I, JAMES WILLIAM CLEGG, a subject of the King of Great Britain, residing at Soho Iron Works, Oldham, 5 in the county of Lancaster, England, have invented new and useful Improvements in Combing Machines, (for which he has obtained a patent in Great Britain, #116,061, application filed February 27, 1918,) of 10 which the following is a specification.

My invention relates to improvements in combing machines of the Nasmith type.

Hitherto it has been customary in machines of this type to support the cylinder 15 cover and the selvage guides from the sliver table.

My present improvements consist essentially in mounting a bracket on or forming an extension of the stand or frame on each 20 side of the combing machine and supporting the cylinder cover and selvage guides adjustably therefrom.

I illustrate my invention by the accompanying drawing which is a side sectional 25 elevation of a combing machine of the Nasmith type fitted with my improved arrangement for supporting and setting the cylinder cover and selvage guides.

In this view—*a* designates the comb cylinder; *b* the brush; *c* the nipper shaft; *d d'* detaching rollers; *e e'* the calendar rollers; *f* the sliver table; *g* the stand or frame of the machine.

For the purposes of my invention, 1 30 mount a bracket *h* on each side of the machine on the stand or frame, and to each bracket *h* bolt or otherwise adjustably secure one of the pair of selvage guides *i*, and also the cylinder cover *j*.

40 The lower end of the cylinder cover *j* is shaped at *j'* to fit and bear against the front

of the beam *g'* and near its upper end it is provided with a back fin or projection *j''* slotted at *j'''* to receive the bolt *k* by which it is adjustably secured to the bracket *h*. 45

By means of the bolt *k* and slot *j'''* or equivalent connection on each side of the machine the cylinder cover *j* can be readily set and adjusted when required relatively to the cylinder *a* and by means of the connecting bolts shown or any suitable equivalents the selvage guides *i* can be adjusted on their supporting brackets *h*. 50

What I claim as my invention and desire to secure by Letters Patent of the United States is:—

1. In a combing machine having a rotatable comb cylinder, the combination of a frame for supporting said cylinder, a bracket secured to said frame adjacent to each end of the cylinder, a cylinder cover adjustably connected to each of said brackets, and selvage guides adjustably connected to said brackets. 60

2. In a combing machine, the combination of a frame, a cylinder mounted for rotation in said frame, a bracket secured to said frame adjacent to the end of said cylinder, a cylinder cover provided with a pair of slotted projections, a bolt carried by each of said brackets and adapted to engage the slot of one of said projections for adjustably securing said cover to said brackets, and selvage guides adjustably connected to said brackets. 70

In testimony whereof I have signed my name to this specification. 75

JAMES WILLIAM CLEGG.
